CLAIM

The ornamental design for a lighting fixture perforated lamp shield, as shown.

DESCRIPTION

FIG. 1 is an isometric view of a lighting fixture perforated lamp shield, showing my new design;

FIG. 2 is an enlarged view of the area shown in circle A in FIG. 1;

FIG. 3 is a front elevational view of a lighting fixture perforated lamp shield showing my new design;

FIG. 4 is a side elevational view thereof;

FIG. 5 is a rear elevational view thereof;

FIG. 6 is a top view thereof;

FIG. 7 is a bottom plan view thereof; and,

FIG. 8 is an isometric view of a lighting fixture perforated shield in a lighting fixture assembly, the lighting fixture and three of the shields shown in broken lines for illustrative purposes only.
